Design for Pipe Stem.

Dec. 1, 1874.

UNITED STATES PATENT OFFICE.

WILLIAM HARVEY, OF NEW YORK, N. Y.

DESIGN FOR PIPE-STEM.

Specification forming part of Design No. 7,907, dated December 1, 1874; application filed October 17, 1874.
[Term of Patent 3½ years.]

To all whom it may concern:

Be it known that I, WILLIAM HARVEY, of the city, county, and State of New York, have invented a new and original Design for a Pipe-Stem, of which the following is a specification:

My design relates to an ornamental or shell-shaped projection applied to the under side of a curved and tapered pipe-stem.

Referring to the accompanying photographic illustration, A indicates the bowl of a pipe; but my design has no reference thereto. The stem B tapers from the base of the bowl, and is curved or bent at a point contiguous to the bowl, as shown. The ornamental protrusion

C has a broad base with a scalloped edge. Its remaining portion is reduced or tapered, and also curved. The special configuration of the surface of stem B may be such as fancy dictates, so long as it is curved and tapered at the base or contiguous to the bowl.

What I claim is—

The design of a curved and tapered pipe-stem, B, and curved projection C, having a scalloped base, as shown.

WILLIAM HARVEY.
